J. A. DEWEY.

SOFA BED.

APPLICATION FILED MAY 5, 1917.

1,379,805.

Patented May 31, 1921.

UNITED STATES PATENT OFFICE.

JOSIAH A. DEWEY, OF SAN FRANCISCO, CALIFORNIA, ASSIGNOR, BY MESNE ASSIGNMENTS, TO MURPHY DOOR BED COMPANY, OF SAN FRANCISCO, CALIFORNIA, A CO-PARTNERSHIP FIRM CONSISTING OF WILLIAM L. MURPHY AND WILLIAM K. WHITE.

SOFA-BED.

1,379,805.

Specification of Letters Patent. Patented May 31, 1921.

Application filed May 5, 1917. Serial No. 166,607.

To all whom it may concern:

Be it known that I, JOSIAH A. DEWEY, a citizen of the United States, and a resident of the city and county of San Francisco, 5 State of California, have invented a new and useful Sofa-Bed, of which the following is a specification.

My invention relates to that type of folding bed commonly known as the davenport 10 or sofa bed.

An object of my invention is to provide a bed with wire fabric and upholstered mattress of full standard size, which is convertible into a sofa by folding.

15 Another object of my invention is to provide a structure of the class described in which the length of the sofa is the width of the bed, the bed folding across its length when converted into the sofa.

20 Another object of my invention is to provide a structure of the class described in which the pillows and bed clothes may be left upon the head of the mattress when the latter is folded.

25 The invention possesses other features of advantage, some of which, with the foregoing, will be set forth in the following description of the preferred form of my invention which is illustrated in the drawings 30 accompanying and forming part of the specification. It is to be understood that I do not limit myself to the showing made by the said drawings and description, as I may adopt variations of the preferred form 35 within the scope of my invention as set forth in the claims.

Referring to the drawings:

Figure 1 is a cross-section of the sofa bed when in the unfolded position to form a bed. 40 Portions of the mattress are broken away to disclose the structure more clearly.

Fig. 2 is a cross-section of the sofa bed when folded to form a sofa. The upholstered mattress and wire fabric are omitted.

45 Fig. 3 is a cross-section of the sofa bed on a smaller scale showing the fabric and mattress in place.

Fig. 4 is an elevation of a portion of the middle frame and the foot frame, showing 50 the method of locking the two frames in position.

Fig. 5 is a cross-section through a modified form of my invention.

My invention comprises a supporting structure or housing 6 in which a bed frame 55 comprising three sections is arranged. The middle section 7 of the bed frame is mounted on pivots 8 set in the housing 6 and is adapted to be turned from a position lying wholly within the housing to an inverted horizontal 60 position in front of the housing. A relatively short foot section 9, Fig. 4, is pivoted to the free end of the middle section 7 to serve as an extension thereof when the structure is unfolded to form a bed. The pivots 65 12 connecting the two sections are set on the sides of section 9 a short distance from the end, and near the end, notches 13 are provided, adapted to engage pins 14 fixed on the side of section 7 when the section 9 is extended into the same plane with section 7.

Means are provided for locking the section 9 in acute angular relation with section 7 preparatory to folding the structure. A link 16 is pivoted upon one side of the section 9 and provided with a hooked end adapted to engage over the pin 14 when the sections are in the desired angular relation to each other. The link 16 is moved into and out of engagement with the pin 14 and 75 held in engagement therewith by a lever 17 pivoted at one end to the section 9 and provided with a pin engaging in a slot 18 formed in the link 16. With the section 9 raised into position as shown in Fig. 4, the 80 lever 17 is pushed downward to engage the hooked end of the link over the pin 14 and hold it thereon, the lever then being substantially at right angles to the link. A foot rail 19 is arranged at the free end of the foot 85 section 9, and legs 21 rigidly fixed upon the end of section 7 provide an outboard support for the bed frame. A wire fabric 22 forming the immediate support for the upholstered mattress 23 is secured to the 90 frames of the two sections 7 and 9, but adjacent the pivots 12 the side fastenings are omitted. Springs 24 connect the fabric to the end of the foot section. A stiffening truss 25 bowed downwardly to clear the fabric and mattress connects the sides of the section 7 near its outer end.

The head section 26 of the bed frame is mounted on pivots 27, set in the housing 6 near the lower front edge, and carries the 105 head end of the fabric 22 secured to the

frame of the section by springs 28. In the sofa form of the structure the head section lies in the lower portion of the housing as shown in Fig. 2, resting upon the bottom rail 29 of the housing. In the bed form shown in Fig. 1, the head section lies at an angle to the horizontal, its head end in the same plane with the middle section 7. The stop 31 set on the housing fixes the upper position of the head section and also the folded position of the middle section 7. The head section is connected to the other bed sections, only through the fabric 22 and it is turned about the pivots 27 to its upper position by the pull of the fabric when the other two sections are extended. The fabric thus performs three functions. It supports the upholstered mattress, forms the operative connection for raising the head frame to support the fabric in proper position in the bed form of the structure and it retains the head frame in the upper position during use of the bed. The fabric is a trifle shorter than the maximum distance between the springs 25 and 28, so that the unfolding movement of the foot section places the springs in tension and draws the fabric tight. The plane in which the fabric is attached to the bed sections when they are in the bed relation, lies below the plane of the pivots 8 and 12 so that once brought to the extended position shown in Fig. 1, the tension of the springs 25 and 28 tends to retain them in that relation. A short head rail 30 is arranged on the end of the head section 26. The mattress 23 of standard thickness rests upon the stretched fabric between the head and foot rails.

In order to facilitate the movement of the bed frames, a tension spring 32 is connected between the housing 6 and a lever arm 33 on each side of section 7. The springs are so arranged that they take the major portion of the weight of the parts both at the end of the folding movement and also at the end of the unfolding movement, and are substantially without tension at the point where the weight is carried entirely by the pivots 8.

When the bed sections are inclosed within the housing, as shown in Fig. 2, the sofa seat is formed by a suitably upholstered seat section 36 which is pivotally mounted on the housing 6 in such a manner that it turns to an inverted position below the middle bed section as shown in Fig. 1, when the latter is unfolded. This is accomplished by forming an extension arm 37 on each end of the seat section and disposing a pivot pin 38 fixed in the housing, near the end of each arm and below the pivot 8. In order to support the rear of the seat section when inverted, a link 41 is pivoted upon a short arm 42 fixed to the seat frame. The link is slotted to engage a pin 43 fixed

on the bed section 7, so that the relative movement between the two sections is provided for. The seat section is thus movably attached to the section 7 and moves with it, the rear end of the seat frame being suspended from section 7 when the section is unfolded and resting on the back of the section when folded to the sofa form, the section 7 in turn resting on the upper face of the stop 31.

The back of the sofa is formed by the suitably upholstered back section 45 mounted on pivots 46 fixed in the housing. Preferably the back section is formed integrally with the top plate 47 so that both swing together about the pivots 46. The back section is provided with a short arm 48 to which is pivoted a link 51. The link is slotted to engage over the fixed pin 52 and a shoulder 53 is formed at the end of the slot so that when the back section is raised to the position indicated by the dotted lines of Fig. 1 the shoulder engages the pin and the link supports the back section in the raised position while the bed frames are being extended. After the bed frames are unfolded the link 51 is disengaged from the pin 52 and the back frame lowered against the stop 54 to form a head board for the bed as shown in Fig. 1.

To convert the sofa into a bed, the back frame is first raised, the fingers being inserted in a recess left in the lower edge. The truss 25 on the section 7 or other convenient portion is then grasped and pulled upward and forward, the movement being strongly assisted by the springs 32. As the section 7 descends to the horizontal position, the springs 32 are again placed in tension so that nearly the entire weight of the parts is balanced by the springs. Lifting the lever 17 releases the foot section which is then turned down into line. The back section is next lowered and the bed is ready to be made up.

By a reversal of the steps just described, the bed is converted into a sofa. Fig. 3 shows the relative position of parts when in the sofa form and how the mattress is folded and inclosed by the fabric. It will be noted that the mattress is supported as in a sling by that portion of the fabric 22 lying between the springs 28 and the first point of support 55 on the section 7.

Fig. 5 shows a modified form of my invention. In this construction I lengthen the head section 26 so that the head rail is closely adjacent the rear of the housing, and correspondingly shorten the foot section, so that it lies above the head of the mattress. Preferably the pivot 27 is lowered somewhat, but the relative relation and movements of the several parts remain without substantial change. The construction shown in Fig. 5 is of value since the mat-

tress in that construction folds but once, the fold between the middle and foot sections being almost eliminated. The space S, Fig. 3, may, if desired, be utilized for the storage of the bed clothing and pillows 56, as shown in Fig. 5.

I claim:

1. In a sofa bed, a housing, a middle section pivoted directly to said housing and adapted to be moved from a position within the housing to a horizontal position without said housing, a foot section pivotally mounted on said middle section and adapted to be turned from a position in acute angular relation to said middle section to one in horizontal extension thereof, a head section pivoted directly to said housing, an upholstered mattress, and a wire fabric connecting the remote ends of said foot and head sections and attached to the sides of said middle section and foot section only

for supporting said mattress in the sofa and the bed form of said sofa bed.

2. In a sofa bed, a housing, a middle section pivoted directly to said housing, a foot section pivotally mounted on said middle section, a head section pivoted directly to said housing, an upholstered mattress, and a wire fabric connected to said head and foot sections for supporting said mattress in horizontal position in the bed form of said sofa bed, and connected to said middle section to form a sling for supporting the folded mattress in the sofa form of said sofa bed.

In testimony whereof, I have hereunto set my hand at San Francisco, California, this 26th day of April, 1917.

JOSIAH A. DEWEY.

In presence of—

C. S. EVANS.
